UNITED STATES PATENT OFFICE.

PAUL T. JONES, OF NEW YORK, N. Y.

RAIL BRACE.

1,406,652.

Specification of Letters Patent. Patented Feb. 14, 1922.

Application filed May 10, 1921. Serial No. 468,391.

To all whom it may concern:

Be it known that I, PAUL T. JONES, a citizen of the United States, and resident of the borough of Manhattan, city, county, and State of New York, have invented certain new and useful Improvements in Rail Braces, of which the following is a disclosure.

My invention relates to railway track furniture and has among its objects the provision of means for preventing the overturning and spreading of rails, which shall be highly efficient, rugged in use, low in cost, and readily manufactured near the points of use.

The novel features of my invention are pointed out with particularity in the appended claim. The invention itself, however, with further objects and advantages, will best be understood from the following description taken with the accompanying drawing in which—

Fig. 1 is an elevation of a rail brace according to my invention illustrating it as applied to a track rail, the rail being shown in section.

Fig. 2 is a plan view of the brace appearing in Fig. 1, the head of the rail being broken away for purposes of illustration.

In the drawing, 1 indicates a tie in a railway track, and 2, a rail resting thereon. On tangent track, the rail is commonly secured to the tie merely by spikes or a tie plate is frequently used between the rail and tie, the plate and rail being spiked to the tie. However, in situations where the rolling stock produces not only a vertical but a lateral stress on the rail, it is often necessary to place a brace against the side of the rails to prevent their overturning or spreading, with consequent derailment. Such braces are also commonly used on bridges and trestles with both track and guard rails.

Rail braces of designs other than mine have developed various defects in use. Owing to their fitting against both the head and the base of the rail, unavoidable wave motion in the rail under heavy rolling stock stresses the spikes of these braces severely in opposite directions, thus producing a maximum loosening effect on the spikes and causing the braces soon to become less effective than when first applied. These braces, contacting with the rail near its top and bottom, have a large proportion of the

metal therein outside the line of the resultant force acting on the rail, with consequent low efficiency in use of material. Difficulty is also experienced in using the common form of rail braces where tie plates are used owing to the tie plate extending beneath the spike hole of the brace. I find, moreover, that prior rail braces are destroyed by the engine wheels in large numbers in cases of derailment.

Rail braces, according to my invention, consist of two integral plane portions 3 and 4 and are of heavy rolled metal plate material such as that used for boilers. The portions 3 and 4 are set at a convenient angle so that when portion 3 is flat on the top of tie 1 the portion 4 abuts the rail 2 substantially at the angle 5 between the head 6 of the rail and the web 7. Preferably, the portion 4 is of such length that the plane of this portion lies substantially in the line of the resultant of the forces exerted on the rail by a locomotive rounding a curve. In case of the present standard rail, such as is illustrated in the drawing, this results in an angle of approximately 135 degrees between portions 3 and 4. In any case, however, the portion 4 should be of such length as to provide clearance between the brace and the spikes 8 or other means used to secure the rail 2 to the tie 1, and is preferably of such length as to provide clearance between the brace and a tie plate. In the case of the standard rail, the rail is of sufficient height so that the portion 4 may be set at the most advantageous angle as regards the resultant of the forces acting on the rail, and also give room between portion 3 and the rail 2 for a tie plate, if one is used.

According to my invention, the portion 3 is spaced from the rail 2 a sufficient distance so that the spikes 8 or other holding members co-operating therewith are inserted into the tie 1 near the outer end of the tie at a place where the wood is solid, no wear from rails or rail-spikes falling on this portion of the tie. Also there is room near the outer end of the tie to use three spikes for each brace, as illustrated, or more may be used if desired.

Braces according to my invention may be secured to the tie by means of spikes 8 identical with those used to hold the rail, or holding means of other form may be used as desired.

While the use of rail braces according to

my invention tends to minimize derailments, such accidents cannot be altogether prevented and I find that braces according to my invention sustain a minimum of damage from derailments. Seemingly, the engine wheels are shifted by the plane inclined portions 4 of the brace so that the wheels run on the horizontal portions 3 and only a few braces are damaged even in cases 10 of serious derailment.

Braces according to my invention, being of low carbon steel, can be manufactured in any shop equipped to do boiler or structural work. They are, moreover, extremely effective, although of moderate weight owing to the fact that the entire weight of metal of portion 4 is substantially in the line of stress, the necessary weight of material being obtained by extending the brace in the direction of the rail rather than by increasing the thickness of the plate from which the braces are made. I prefer to make braces according to my invention of three-quarter inch plate and find, when using this 25 material, that the brace does not need to be as wide as the tie in order to be strong enough for all practical purposes, and I find it advantageous that the brace be an inch or more narrower than the tie in order that 30 it may be adjusted laterally of the tie in case the tie may be unsound near one edge, my braces being usually five inches along the rail.

In operation, a brace according to my invention is subjected to stress in only one direction. When the wheels of rolling stock force the rail head downwardly, or downwardly and outwardly, the brace is placed 35 under compression as will be evident from 40 an inspection of the drawing. The brace being entirely free from contact with the base of the rail, there is no opportunity for

the rail to produce any tension or bending effect on the brace when the rail moves upwardly, as always occurs at times in practice. Consequently, the spikes, or other holding means, act with maximum efficiency, it being well known that stresses in alternate directions tend to loosen spikes and the like. 45

It will be seen that a rail brace according to my invention is simple, economical, and efficient. It will be seen, moreover, owing to the fact that the maximum stresses on rail braces commonly fall on those used at curves, braces according to my invention 50 are designed to develop their maximum efficiency in such a use. They are, however, well adapted to and have ample strength for use on bridges, trestles, guard rails, switches and switch points, reinforcing track to keep 55 old ties in service, patching up after wrecks, or wherever the grip of the rail spikes is insufficient. In all such places my braces are readily applied and afford firm support to 60 the rail. 65

Having thus described my invention, I claim:

The combination of a railway rail structure of ordinary type, a wooden tie supporting said rail structure, a brace composed of two plate portions, one of which lies on top of said tie and the other of which inclines upwardly from said tie and contacts with said rail at the angle between the head of the rail and the vertical web thereof, and a plurality of single-headed metal fasteners for said brace entering the wood of said tie and spaced in the direction longitudinally of the rail, said brace permitting upward movement of said rail structure under traffic 70 without stressing the brace whereby said fasteners are free from stress except during the downward movement of the rail. 75 80

PAUL T. JONES.
